UNITED STATES PATENT OFFICE

FRANK A. FALK, OF STACYVILLE, IOWA, ASSIGNOR TO CHICAGO FORGING & MANUFACTURING CO., OF CHICAGO, ILLINOIS, A CORPORATION OF ILLINOIS

HOOD LATCH

Application filed January 2, 1932. Serial No. 584,462.

My invention relates to an improvement in automobile hood latches and is particularly adaptable to employment with multiple hinge hood closures for automobiles. One object is the provision of such a device which shall include an exterior handle and interior latching means positioned within the hood closure. Another object is the provision of a device which shall include a single exterior handle whereby a plurality of interior latching means may be moved into and out of securing engagement with a keeper or keepers. Other objects will appear from time to time in the course of the specification and claims.

I illustrate my invention more or less diagrammatically in the accompanying drawings, wherein—

Figure 1 is a side elevation;

Figure 2 is a partial interior elevation on an enlarged scale;

Figure 3 is a section on the line 3—3 of Figure 2;

Figure 4 is a view similar to Figure 2 with the parts in unlatched position;

Figure 5 is a section on the line 5—5 of Figure 4; and

Figure 6 is a section on the line 6—6 of Figure 4.

Like parts are indicated by like symbols throughout the specification and drawings.

Referring to the drawings, A generally indicates a portion of the automobile frame, A¹ is the radiator, A² is the lower hinge member of the automobile closure, being hinged to the upper member A³ which is hinged to the automobile as at A⁴. A¹¹ indicates the dash or cowl of the automobile.

Positioned within said closure and spaced more or less therewithin are the keeper brackets generally indicated as B which include a bottom flange B¹, an upwardly extending portion B² and a hook portion B³ inclined downwardly and outwardly toward the inner face of the hood closure. The bracket or keeper so formed may be secured to the frame by any suitable securing means. I illustrate the bolt B⁴ with the nut B⁵.

Rotatably mounted upon the inner face of the closure for rotation about a generally horizontal axis is the rock shaft or rod C.

I illustrate it as rotatably supported with sleeves or bearings C¹ adjacent the central portion thereof, and C² adjacent the ends thereof. Beyond the bearing C² the ends of the rod are curved as at C³ and terminate in portions C⁴ which extend in general parallelism with the rod itself. It will be understood that whereas I have shown a particular type of crank end for the rod C, that I do not wish to be limited specifically to the particular crank herein shown, although I find it an efficient solution of the problem. The keeper also may be varied in form and location, depending upon the nature of the crank employed.

In order to rotate the rod C in such fashion as to move the crank members C³ C⁴ into and out of latching association with the keeper hooks B³ I employ the following mechanism. I provide a central offset D in the form of a Z having what I may call an upper angle D¹ and a lower angle D². I illustrate it as located between the two central bearing sleeves C¹, although its location in relation to the length of the rod may be varied if desired. In the particular exemplification of my invention herein shown, the offset D lies in a radial plane at a substantial angle to the radial plane in which the cranks C³ C⁴ lie. This will be clear for example from Figure 3. However, if desired, the offset D may be otherwise positioned, for example in a non-radial plane. Its rectilinear form is in the present instance advantageous but under some circumstances it also may be departed from. In order to rotate the offset and thus rotate the rod C, I employ an exterior handle E which may be mounted on a handle shaft E¹. Held against movement in relation to the handle E on the shaft E¹ is a cam carrying plate or base E². The assembly may be held together for example by the nut E³ in mesh with the screwthreaded end portion E⁴ of the shaft E¹. I illustrate this as an example of satisfactory means for holding the parts together but other suitable means may be employed.

Extending outwardly from the base portion of the cam are two cam members E⁵ E⁶ respectively. E⁵ is shown as a closed loop de-

fining the cam slot E^7 through which passes one end of the central arm of the Z . E^8 is indicated as a compound member defining the open ended slot E^8 through which the 5 central arm of the Z also passes. It will be seen, for example from Figures 2, 4 and 6, that the straight central arm of the Z passes through the two cam slots in question, one adjacent each end of the arm or, stated 10 otherwise, adjacent respectively to the angles D^1 and D^2 . The cams are radially spaced from the axis of rotation of the base plate E^2 , on opposite sides thereof. Rotation of the cam assembly may be limited by contact 15 with the opposite ends of the slot E^7 with the penetrating portion of the rod. It will be noted that the axis of rotation of the exterior handle E , if extended, intersects the axis of rotation of the rod C . 20

It will be realized that whereas I have described and shown a practical and operative device, nevertheless many changes may be made in the size, shape, number and disposition of parts without departing from the 25 spirit of my invention. I therefore wish my description and drawings to be taken as in a broad sense illustrative and diagrammatic rather than as limiting me to my specific showing.

The use and operation of my invention are 30 as follows:

Assume that the securing means or cranks are in the unlocked position in which they are shown for example in Figures 4 and 5 35 with the cams in unlocking position. If the operator rotates the handle E in counter-clockwise direction, referring to the parts in the position in which they are shown in Figure 4, he moves the cams through an arc of 40 in the neighborhood of 90 degrees. This rotation causes a rotation of the rod through an arc sufficient to move the cranks from the unlocked position in which they are shown in section in Figure 5 to the locked position 45 in which they are shown in section in Figure 3. The cam connection between the two cam slots E^7 and E^8 and the central portion of the Z constrains the rod as a whole to this locking rotation in response to rotation of the 50 handle E . A reverse rotation of the handle E in the opposite direction returns the parts to the unlocking position, with the cranks out of vertical alignment with the keepers, whereby the closure may readily be 55 opened or raised.

I claim:

1. For use with a latching device for the 60 multiple hinge closure of an automobile hood, a rod rotatably mounted upon the inner face of the closure for rotation about a generally horizontal axis, and means for rotating said rod including an exterior handle mounted for rotation about an axis generally perpendicular to the axis of rotation of the 65 rod, an offset of said rod including a portion

generally inclined to said rod, and an actuating member associated with and rotatable in unison with said handle, said actuating member including a cam slot continuously penetrated by the offset portion of said rod. 70

2. For use with a latching device for the 75 multiple hinge closure of an automobile hood, a rod rotatably mounted upon the inner face of the closure for rotation about a generally horizontal axis, and means for rotating said rod including an exterior handle mounted for rotation about an axis generally perpendicular to the axis of rotation of the rod, an offset of said rod including a portion generally inclined to said rod and extending 80 on opposite sides of the axis of rotation of the rod, and an actuating member associated with and rotatable in unison with said handle, said actuating member including a cam slot penetrated by the offset portion of said rod. 85

3. For use with a latching device for the 90 multiple hinge closure of an automobile hood, a rod rotatably mounted upon the inner face of the closure for rotation about a generally horizontal axis, and means for rotating said rod including an exterior handle mounted for rotation about an axis generally perpendicular to the axis of rotation of the rod, an offset of said rod including a rectilinear portion generally inclined to said rod, and an actuating member associated with and rotatable in unison with said handle, said actuating member including a cam slot penetrated by the rectilinear offset portion of 95 said rod. 100

4. For use with a latching device for the 105 multiple hinge closure of an automobile hood, a rod rotatably mounted upon the inner face of the closure for rotation about a generally horizontal axis, and means for rotating said rod including an exterior handle mounted for rotation about an axis generally perpendicular to the axis of rotation of the rod, an offset of said rod including a portion generally inclined to said rod, and a plurality 110 of actuating members associated with and rotatable in unison with said handle, said actuating members including cam slots penetrated by the offset portion of said rod. 115

5. For use with a latching device for the 120 multiple hinge closure of an automobile hood, a rod rotatably mounted upon the inner face of the closure for rotation about a generally horizontal axis, and means for rotating said rod including an exterior handle mounted for rotation about an axis generally perpendicular to the axis of rotation of the rod, an offset of said rod including a portion generally inclined to said rod, extending 125 on opposite sides of the axis of rotation of the shaft, and a plurality of actuating members associated with and rotatable in unison with said handle, said actuating members including cam slots penetrated by the offset portion of said rod. 130

6. For use with a latching device for the multiple hinge closure of an automobile hood, a rod rotatably mounted upon the inner face of the closure for rotation about a generally horizontal axis, and means for rotating said rod including an exterior handle mounted for rotation about an axis generally perpendicular to the axis of rotation of the rod, an offset of said rod including a portion generally inclined to said rod, and a plurality of actuating members associated with and rotatable in unison with said handle, said actuating members including cam slots penetrated by the offset portion of said rod, said actuating members being positioned on opposite sides of the axis of rotation of said handle.

7. For use with a latching device for the multiple hinge closure of an automobile hood, a rod rotatably mounted upon the inner face of the closure for rotation about a generally horizontal axis, and means for rotating said rod including an exterior handle mounted for rotation about an axis generally perpendicular to the axis of rotation of the rod, a reverse offset of said rod including a portion generally inclined to and extending across the axis of said rod, and a plurality of actuating members associated with and rotatable in unison with said handle, said actuating members including cam slots penetrated by the offset portion of said rod, said offset portion of the rod being rectilinear.

8. For use with a latching device for the multiple hinge closure of an automobile hood, a rod rotatably mounted upon the inner face of the closure for rotation about a generally horizontal axis, and means for rotating said rod including an exterior handle mounted for rotation about an axis generally perpendicular to the axis of rotation of the rod, a reverse offset of said rod including a portion generally inclined to and extending across the axis of said rod, and an actuating member associated with and rotatable in unison with said handle, said actuating member including a cam slot penetrated by the offset portion of said rod, said actuating member being radially spaced from the axis of rotation of the handle.

9. For use with a latching device for the multiple hinge closure of an automobile hood, a rod rotatably mounted upon the inner face of the closure for rotation about a generally horizontal axis, and means for rotating said rod including an exterior handle mounted for rotation about an axis generally perpendicular to the axis of rotation of the rod, a double offset of said rod including a portion generally inclined to and crossing the axis of said rod, and an operating member associated with and rotatable in unison with said handle, said operating member including a cam slot penetrated by the

offset portion of said rod, the axes of rotation of the rod and of the handle being perpendicular to each other.

Signed at Osage county of Mitchell and State of Iowa, this 9th day of December 70
1931.
